METAL WINDOW WITH METAL WEATHER STRIPS

Milton Alexander, Richmond Hill, and Fred Wiesler, Jamaica, N. Y., assignors to Suburban Bronze Works, Inc., a corporation of New York

Application May 16, 1939, Serial No. 273,854

1 Claim. (Cl. 189—65)

This invention relates to improvements in metal weatherstrips for metal windows. The object of the invention is to provide an improved metal weatherstrip which may be easily manufactured and installed or attached to metal windows. Particularly one object of the invention is to provide a metal weatherstrip in the form of a channel adapted to fit within the channeled members of the metal window sash and operated automatically to function as a weatherstrip.

Accordingly the invention is embodied in a metal window having its sashes constructed of channeled frame member in combination with channeled metal weatherstrips adapted to fit within the channels of the sash together with means for pressing the weatherstrip members outward against the window frame. In the accompanying drawing illustrating the invention

Fig. 1 is a vertical sectional view through the metal window equipped with the improved weatherstrip, parts are broken away and parts are omitted.

Fig. 2 is a fragmentary sectional view on the line 2—2 of Fig. 1.

Fig. 3 is a horizontal sectional view through the two window sashes taken on the line marked 3 in Fig. 1.

Fig. 4 is an inside view of the window showing the sash members and the weatherstrips in outline.

The window casing is generally indicated in Figs. 1 and 2 by the lower sill member 10, the top member 11 and the side members 12. The members are shown in general sectional outline. The top and side members are formed with channeled recesses marked 14 within which the window sash members slide and which are engaged by the weatherstrips. At the bottom the sill member 10 has a stepped portion 15 to be engaged by the weatherstrip.

The upper window sash is formed of the usual four members 17 which enclose the window pane 18. The lower member 17 forms an inwardly projecting trough 19. The lower window sash is formed of the usual four member 20 which enclose the window pane 21. The upper member 20 is formed with an overhang portion 22 which hooks into the trough 19 in the usual manner. Each sash frame member 17 and 20 is formed with an outwardly facing channel 25. In the overhang 22 one side of the channel 25 is formed by a separate member 26.

There are three weatherstrips for the upper window. They are marked 27, 28 and 29 in

Fig. 4. There are four weatherstrips for the lower window and they are marked 30, 31, 32 and 33 in Fig. 4. Each weatherstrip is in the form of an outwardly facing channel having the two channel wing portions or members 35, 35 which are joined by the bridge member 36, see Fig. 3. The wings may be stiffened by having the metal folded as shown. The dimensions of the weatherstrips are such as they have a tight sliding fit within the sash channels 25 as will be understood.

The weatherstrips are pressed outward by means of spring bullet catches 40, the buttons 41 of said catches pressing against the bridge members 36 of the weatherstrips. The bullet catches in turn are held in the bridge members of the sash channels. The bullet catches are spaced suitable distances apart so that the weatherstrip will be under even pressure throughout its length as will be understood.

The weatherstrips are held within the sash frames by studs 45 or by screws as at 46 in Fig. 2. The studs have washers 47 or like means which prevent the weatherstrips from being pressed too far out of the sash channels. Thus when the upper window is lowered the studs 45 in the top member 17 prevents the top weatherstrip from moving too far upward out of the top, and the screws 46 prevent the middle weatherstrip from being pressed too far downward from the lower sash. The studs in the side frames hold the strips in position before installation.

The weatherstrips according to this invention are easily cut off in suitable lengths from long strips or lengths formed by machinery in the proper cross sectional dimensions. The bullet catches and holding studs or screws are inserted from the outside and require but little work.

We claim:

In a window structure, a metal window frame comprising a top, two sides and a sill, said top and sides having inwardly facing grooves, an upper and a lower metal window sash having longitudinal grooves facing and sliding within said frame side grooves, said upper window sash having an upwardly facing groove adapted to engage within an inwardly facing groove in said frame top, when the window is closed, weatherstrips in said sash grooves, said sashes having overlapping portions formed with grooves facing each other in overlapping relation, the groove in the lower sash fitting over the groove in the upper sash, a separate member in the overlapping groove in the lower sash to form a weather-

strip groove therein, a weatherstrip in said weatherstrip groove, a downwardly facing bottom groove in the said lower sash, a weatherstrip in said bottom groove to engage said window sill, 5 all of the aforesaid weatherstrips being channels occupying the full widths of their respective grooves, the legs of said channels pointing outward from said grooves and projecting therefrom, spring means secured to the sashes and engaging 10 the weatherstrips therein to move the same out-

ward into weathertight relation with the bottom of the corresponding frame grooves and away from the bottoms of said weatherstrip grooves, the bottom weatherstrip being moved into weathertight relation with the window sill when 5 the window is closed and means in the sashes for limiting said outward movements of said weatherstrips.

MILTON ALEXANDER.

FRED WIESLER.
